FIG. 1 is a right, front perspective view of a rear portion of a vehicle showing my new design;

FIG. 2 is a left, front perspective view thereof;

FIG. 3 is a left, rear perspective view thereof;

FIG. 4 is a right, rear perspective view thereof;

FIG. 5 is a front view thereof;

FIG. 6 is a right side view thereof;

In FIGS. 1–8, the inventive rear portion is shown rearward of the larger broken line. The rest of the vehicle that is located forward of the larger broken line is shown in de-emphasized and half-tone portions. These portions are included to show environmental structure and form no part of the claimed design. Also, in FIGS. 1, 4, 5, 6, and 8, the smaller broken line forms no part of the invention, but instead is included to show environmental structure, namely, the fuel door.

The portions of the vehicle shown throughout the drawing views in a de-emphasized and half-tone form outside the broken lines and the broken lines representing the boundary and configuration of what is claimed as the design are all for environmental and illustrative purposes and form no part of the claimed design.
